UNITED STATES PATENT OFFICE.

HERBERT F. PRESCOTT, OF DETROIT, MICHIGAN.

SOAP-CONTAINER.

1,108,083.

Specification of Letters Patent.

Patented Aug. 18, 1914.

Application filed May 31, 1913. Serial No. 771,020.

To all whom it may concern:

Be it known that I, HERBERT F. PRESCOTT, a citizen of the United States of America, residing at Detroit, in the county of Wayne and State of Michigan, have invented certain new and useful improvements in Soap-Containers, of which the following is a specification, reference being had therein to the accompanying drawings.

10 My invention relates to a soap container and more particularly to a container for liquid soap adapted for use with a wash board.

The invention consists in the provision of 15 a simple device that may be easily and cheaply manufactured; in a structure that may be applied to wash-boards of varying sizes; in a device which when applied to a wash-board, and in use, is in proper position 20 to discharge the soap onto the working face of the board but when not in use will not interfere with the operation of washing; further in certain details of construction and arrangements of parts as will more fully 25 hereinafter appear.

In the drawings,—Figure 1 is a perspective view of a wash-board with my improved device applied thereto; Fig. 2 is a top plan view of the container and its support; and Fig. 3 is a side elevation thereof.

A designates the wash-board having the working face B thereof of usual construction, and C is a guard extending above the working face B to adjacent the top of the 35 board. This guard extends from the front face B rearwardly and is secured to the sides D of the board at their rear edges E.

F is the receptacle or container proper for the liquid soap, and while it may be of any 40 desired configuration, preferably is elongated and rather shallow in width. This receptacle is provided with a plurality of perforations G adjacent the inner, upper edge H thereof, and is connected in any suitable manner, as by soldering to a rod I, the latter being arranged adjacent the forward top edge J of the receptacle F. The rod I has the ends thereof projecting upon opposite sides of the member F and these projections are journaled in suitable supports upon the board A. Preferably the projections on the rod are arranged within tubular members K having flattened ends L secured by means of screws or other suitable devices M 50 to the sides D. Within each of the members K is interposed a coil-spring N. By

this arrangement the springs N normally hold the container F centrally between the members K, but when it is desired to remove the receptacle F it is merely necessary to move it to one side, against the tension of 60 one of the springs, until one of the projecting ends of the member I is disengaged from one of the members K. The opposite end of the member I may then be readily withdrawn from the other bearing K.

When attached to the board the flattened ends of the members K are secured to the front edges O of the sides D, which positions the container within the space in rear of the 70 edges O and therefore, the container will not interfere with the operation of washing.

In use the receptacle or container for the liquid soap is normally suspended as shown in Fig. 1. When it is desired to discharge 75 the contents onto the board the member F is rocked outwardly by hand until the receptacle is inverted, when the liquid soap will discharge from the perforations G. When released, the receptacle will return to 80 its normal position.

What I claim as my invention is:—

1. The combination with a wash-board including the working face and the spaced sides having portions extending above the 85 working face, and a guard extending from the working face rearwardly, forming a space between said guard and the plane of the front edges of said sides, of a comparatively narrow receptacle for liquid soap arranged within said space and having the front face thereof substantially within the plane of the outer edges of the sides, said receptacle having a perforated top, and a pivotal connection between the sides of the 90 receptacle permitting the inverting of the latter upon an outward rocking movement of the bottom of the receptacle.

2. The combination with a wash board including the working face and the spaced 100 sides having portions extending above the working face, and a guard extending from the working face rearwardly, forming a space between said guard and the plane of the front edges of said sides, of a comparatively narrow receptacle for liquid soap arranged within said space and having the front face thereof substantially within the plane of the outer edges of the sides, said receptacle having a perforated top, a pivotal connection between the sides of the 105 receptacle permitting the inverting of the latter upon an outward rocking movement of the bottom of the receptacle.

latter upon an outward rocking movement of the bottom of the receptacle, said connection comprising a rod extending longitudinally of and connected to the receptacle adjacent the outer edge of the top, and pivotal connections between the rod and said sides.

3. The combination with a comparatively narrow receptacle provided with a perforated top, of a rod rigidly connected to the top adjacent one edge thereof, tubular members sleeved upon opposite ends of the rod,

15 springs interposed between the ends of the rod and the bases of the tubular members, the latter being provided with apertured, flattened outer ends, for the purpose described.

In testimony whereof I affix my signature in presence of two witnesses.

HERBERT F. PRESCOTT.
